UNITED STATES PATENT OFFICE.

WILLIAM S. FOSTER, OF UTICA, NEW YORK.

DESIGN FOR A BEDSTEAD.

SPECIFICATION forming part of Design No. 26,854, dated March 30, 1897.

Application filed February 8, 1897. Serial No. 622,549. Term of patent 7 years.

To all whom it may concern:

Be it known that I, WILLIAM S. FOSTER, a citizen of the United States, residing at Utica, in the county of Oneida and State of New York, have invented and produced a new and original Design for a Bedstead, of which the following is a specification, reference being had to the accompanying drawings, showing the same.

Figure 1 is a perspective view of a bedstead of my design. Fig. 2 is an enlarged detail of an ornamental part of the construction.

The feature of my design is the bedstead consisting of posts and cross-bars and spindle,

as shown, and particularly the ornament *a* of design shown at the joint between the vertical spindles and horizontal cross-bars. 15

What I claim is—

The design of a bedstead herein shown and described. 20

In witness whereof I have hereunto set my hand, at Utica, New York, this 3d day of February, 1897.

WILLIAM S. FOSTER.
